CLAIM

The ornamental design for a support post for a food guard system, as shown and described.

DESCRIPTION

FIG. 1 illustrates a perspective view of the support post secured to a food guard shield.

FIG. 2 illustrates a left-side perspective view of the support post shown in FIG. 1.

FIG. 3 illustrates a top plan view of the support post shown in FIG. 2.

FIG. 4 illustrates a side plan view of the support post shown in FIG. 2.

FIG. 5 illustrates a bottom plan view of the support post shown in FIG. 2; and,

FIG. 6 illustrates a front plan view of the support post shown in FIG. 2.

The broken lines in the drawings are for illustrative purposes only and form no part of the claimed design.
